UNITED STATES PATENT OFFICE.

JOHN FRANK MARTIN, OF CHARLES TOWN, WEST VIRGINIA.

SHOE-SOLE.

1,364,570.

Specification of Letters Patent.

Patented Jan. 4, 1921.

Application filed November 9, 1917. Serial No. 201,095.

To all whom it may concern:

Be it known that I, JOHN F. MARTIN, a citizen of the United States, residing at Charles Town, in the county of Jefferson and State of West Virginia, have invented 5 certain new and useful Improvements in Shoe-Soles; and I do hereby declare the following to be a full, clear, and exact description of the invention, such as will enable others skilled in the art to which it appertains to make and use the same.

This invention relates to improvements in shoe soles and has for one of its objects the provision of a device of this character which 15 will relieve the pressure upon the ball of the foot and toes, thereby obviating calli and corns caused thereby.

Another object of this invention is the provision of means for supporting the arch 20 of the shoe, thereby obviating falling arches to feet and which will strengthen falling arches when used thereon.

A further object of this invention is the provision of a shoe sole of the above stated 25 character, which shall be simple, durable and efficient, and which may be manufactured and sold at a comparatively low cost.

With these and other objects in view as 30 will become more apparent as the description proceeds, the invention consists in certain novel features of construction, combination and arrangement of parts as will be hereinafter more fully described and claimed.

35 For a complete understanding of my invention, reference is to be had to the following description and accompanying drawings, in which:—

Figure 1 is a bottom plan view of a shoe 40 sole constructed in accordance with my invention,

Fig. 2 is a longitudinal sectional view of the same, illustrating the inclination of the arch support and taken on line 2—2 of Fig. 45 1, looking in the direction illustrated by the arrows.

Fig. 3 is a transverse sectional view illustrating the concave of the ball portion of

the sole taken on line 3—3 of Fig. 1, looking in the direction indicated by the arrows.

50

Fig. 4 is an end view of the heel portion of the sole.

Referring in detail to the drawing, the numeral 1 indicates as an entirety, a shoe sole which is preferably constructed from 55 a suitable composition of material and consists of a ball portion 2, instep portion 3, and a heel portion 4. The ball portion 2 of the shoe sole has formed upon its outer face a raised portion 5 which is concaved as 60 clearly illustrated in Figs. 2 and 3 to form a recess 6 upon the outer face of the shoe sole for the purpose of forming a cushion for the ball and toes of a foot. The raised portion 5 is spaced from the edges of the 65 sole for the purpose of providing a space 7 to which the shoe upper may be secured in the ordinary manner by stitches and which will prevent the stitching from coming in contact with the ground thereby obviating 70 wear thereof. The recess or depression 6 will permit flexing or sagging of the sole at such a point when walking or standing thereon, thereby forming a cushion to the ball and toes of the foot which prevents calli, 75 corns and bunions.

A raised extension 8 is formed upon the raised portion 5 and extends rearwardly under the instep portion 3 terminating in an abrupt shoulder 9 at the beginning of the 80 heel portion 4 and is adapted to contact with the ordinary heel of a shoe (not shown). The outer or upper face of the raised portion 8 is inclined downwardly from the abrupt shoulder 9 until it communicates in a 85 plane with the bottom wall of the recess 6 for the purpose of conforming to the contour of the outer face of the sole. When the foot is positioned upon the sole, permitting the heel to rest upon the heel portion 4, the arch of the sole will be supported by the raised extension 8 obviating falling arches and which will support falling arches 90 when applied thereto.

While I have shown and described the 95 preferred embodiment of my invention, it

will be understood that minor changes in construction, combination and arrangement of parts may be made without departing from the spirit and scope of the invention
5 as claimed.

Having thus described my invention, what I claim is:—

As a new article of manufacture, a shoe sole having a depression adapted to permit
10 flexing of the sole when under weight, a raised portion surrounding said depression,

and a projection formed on the raised portion to support the arch portion of the sole of the shoe and inclined downwardly and terminating in a plane with the depression. 15

In testimony whereof I affix my signature in presence of two witnesses.

JOHN FRANK MARTIN.
